CAR TRUCK

James A. Shafer, East Cleveland, Ohio, assignor
to National Malleable and Steel Castings Com-
pany, Cleveland, Ohio, a corporation of Ohio

Application December 19, 1931; Serial No. 582,002

15 Claims. (Cl. 105—197)

It has been found that where sufficient spring capacity is provided in railway car trucks to support the heaviest loads, the springs are sometimes too stiff to give the desired cushioning action under relatively light loads. Moreover, where all the springs are alike, there is a tendency, under certain speed and track conditions, for the oscillations of the springs to increase according to the principles of harmonic motion. This is obviously undesirable because among other things the motion may become so great that the springs are driven solid with consequent damage to the lading and to the springs themselves.

An object of the present invention is, hence, to overcome these disadvantages through the provision of an improved construction in which the bolster is supported on a side frame member through springs, and in which additional springs, preferably under initial compression, are provided for engaging the bolster for cushioning movements of the same after it has traveled a predetermined distance while compressing the first named springs, and for damping out oscillations. A more specific object of the invention is to provide such a spring construction in a car truck of the character disclosed in my copending application Ser. No. 458,480, filed June 6, 1930, without the need for expensive or complicated alterations and with the addition of but few and simple parts. Another object is the provision of a construction which is simple and relatively inexpensive to manufacture, convenient to assemble, and sturdy and durable in service. Other objects and advantages of the invention will be in part pointed out and in part apparent in connection with the following detailed description of a preferred embodiment of the invention, reference being had to the accompanying drawings wherein Fig. 1 is a vertical central section taken longitudinally of the side frame of a car truck embodying my present invention. The side frame is shown broken away at either end. Fig. 2 is a section taken on the line 2—2 of Fig. 1 looking in the direction of the arrows, and showing assembling means in place.

In the drawings, there is shown at A a side frame having tension members C and a window opening D for receiving an end of bolster B. The side frame is shown as preferably having a shelf 2 at the bottom of the window, and a box-shaped portion 3 formed below the shelf 2 and joining the tension members C. In order to support the bolster B on the side frame, the end of the bolster is shown formed with spring receiving recesses 4 adapted to surround the upper end of coil springs

5, two separate sets of coil springs, each consisting of inner and outer coils, being shown, though obviously any other convenient type of spring could be employed. The lower ends of these springs are shown as resting upon spring plates 6 supported on the shelf 2 and having upwardly extending projections 7 for centering the springs. These springs may be arranged so that their axes are at right angles to the longitudinal center-line of the side frame. Lugs 8 are shown extending downwardly from the under side of the top of the bolster for centering the upper ends of the springs. Openings may be provided in the bolster lugs 8 and the spring plate projections 7 for receiving pins or bolts 9 for maintaining the springs in assembled relation with respect to the bolster when the side frame is removed. The general arrangement of parts thus far described is shown in my copending application above referred to.

As shown in Fig. 1, the shelf 2 on the side frame is formed with openings 10 adapted to receive downwardly extending spaced projections 11 formed on the bolster. These projections on the bolster serve a double purpose in that they not only tie the side frames together through coaction with the side walls of the openings 10 but also cooperate with the springs 12 as hereinafter further pointed out. Two sets of springs 12 are shown as each consisting of inner and outer coils seated on the bottom of the box portion 3 of the side frame and positioned between lugs 14 and 15 formed on the side frame. As shown, the springs 5 are located entirely above the shelf 2, and the springs 12 below the same, the upper springs lying transversely of the side frame and the lower springs longitudinally thereof, with the upper and lower springs in overlapping relation with respect to the horizontal plane of the shelf 2. However, this arrangement while preferred is not essential so far as the present invention is concerned. Each set of springs 12 is provided with a spring cap 16 whose upper face is adapted to be engaged by the lower end of one of the projections 11 on the bolster when the latter

is under more than a light load or upon oscillations being introduced in the upper springs 5 so as to cause the bolster to move downwardly sufficiently to engage the spring cap. The shelf 2 as shown is formed with downwardly extending generally annular shaped flanges 17 which serve not only to increase the bearing area between lugs 14 and the side frame but also as abutments for collars or washers 18 and 19 which are operatively interposed between the flanges 17 and the upper

faces of the spring caps. These washers are adapted to seat on the spring caps 16 and are preferably of the same internal diameter as the opening in the shelf 2. Moreover, the lower ends 5 of the projections 11 on the bolster extend downwardly through and beyond the shelf and the flanges 17 so that they center the washers or collars with respect to the other parts of the construction. In this manner, the bolster upon the 10 imposition thereon of a relatively heavy load will move downwardly a predetermined distance, and then contact with the top of the spring caps 16 on the springs 12. The springs 12 are thus brought into action with the effect that they resist continued downward movement of the bolster. 15 On the other hand, upon upward motion of the bolster, the lifting action of the springs 12 is only imparted to the bolster up to the point at which the collar 18 or 19, respectively, abuts against the flange 17 on the shelf. In this way, the action of 20 either spring 12 on the rebound is withdrawn at the time the collar contacts with the shelf, such withdrawal of said spring action contributing further to the checking of the oscillation.

25 It will be noted that the collar 19 is shown somewhat thicker than the collar 18, and accordingly the spring 12 which cooperates with the former is under greater initial compression than is the other spring 12. However, both collars 30 may be the same size, in which case both springs 12 will operate practically in unison. Where the two collars are of different heights, it will be apparent that the bolster on downward movement will first contact with the spring cap 16 on spring 35 12 which cooperates with washer 18 and subsequently with spring cap 16 on spring 12 which cooperates with washer 19, so that the two springs will be successively brought into and out of action, thus increasing the tendency of the springs 12 40 to damp out excessive oscillations.

The inner coils of the upper springs 5 may be so related to the bolster and of such capacity that when the car is empty and the bolster, in recoiling, reaches a predetermined height above its 45 normal (or rest) position, the inner coils aforesaid are released. This release of said coils aids in damping said oscillations.

As a more specific illustration of the mode of operation of the embodiment here disclosed, assume the car to be empty, in which case the bolster may be supported only by the upper springs 5. If the bolster now starts to oscillate, a downward movement of predetermined extent brings the bolster into engagement with cap 16 50 of the lower spring 12 at the left in Fig. 1. The increasing resistance offered by said spring 12 acts to break up the oscillation. At the same time, the inner coils of the upper springs 5, as pointed out above, may be so constructed and arranged that, should the oscillations aforesaid persist and their amplitude increase said inner coils will be released upon a predetermined extent of recoil of the bolster above its normal position. Such release of the inner coils aids in breaking 55 up the oscillations. When the car has a medium or average load, the bolster may be supported both by springs 5 and the aforesaid left hand spring 12, and the right hand spring 12 may be so disposed with relation to the bolster that a further downward movement thereof of predetermined extent brings said bolster into engagement 60 with the cap 16 of said right hand spring, the increased resistance of the latter breaking up the oscillation, and recoil of the bolster beyond the 65 point at which collar 18 engages the associated 70

projection 17 releasing the left hand spring with further checking of the oscillation. When the car is fully loaded, the bolster may engage all four springs, a very slight recoil freeing the right hand spring 12 with resultant checking of oscillation. 5

The capacities, numbers and sizes of the springs, and the amounts of initial compression of certain of the springs, may obviously be varied with the load to be imposed on the bolster, and these details are within the grasp of those skilled in the art. The ratio of initially compressed springs to other springs may also vary. In addition, my invention provides a spring capacity that varies with the weight of the lading. Under light loads, the bolster is supported by a spring capacity to effectively carry the load and as the load increases other springs successively come into play to add to the capacity of the first 20

For assembly purposes spring caps 16 are shown as formed separate from cooperating plugs 21 which may extend into openings 20 in the spring caps and have flanges 22 for engaging shoulders 23 formed on the spring caps. These plugs may be formed hollow and preferably extend downwardly beyond the spring caps for centering the caps on the springs 12, and upwardly above the spring caps into openings 24 in the bolster projections 11 for centering the spring caps with respect to the bolster. The shoulders 22 preferably extend outwardly sufficiently from the plugs to prevent the plugs from being thrown up too far into the openings 24. That is to say, the shoulders 22 may be adapted to engage the bottoms of the projections 11. 25

It will be understood that in order to incorporate the present novel features described in the construction shown in my stated application, it is only necessary to provide one collar or washer 18 or 19 per spring. In order to provide for the insertion of the collars I have shown in Fig. 2 a member 30 having an outwardly extending flange 31 for engaging shoulders 23 on the spring caps 16. This member 30 may be threaded as at 32 at its lower end and inserted in the construction after the plugs 21 have been removed. The member 31 extends outwardly through opening 33 at the bottom of the side frame and a nut 34 cooperating with the threads 32 and a washer 35 seated against the bottom of the side frame, serves to draw down on the spring cap to compress the springs sufficiently to permit the insertion of the collars 18 and 19. After the collars are in place the nut 34 is released, the member 30 removed, and the plugs replaced. The assembly of the other parts will no doubt be apparent, but it may be noted that the spring caps 16 can be put in place after the springs 12 are in position, and that the plugs 21, after the removal of member 30 and insertion of collars 18 and 19, can be manually inserted through the openings 10 before the bolster and side frame are assembled. To assemble the bolster and side frame it is merely necessary to raise the bolster sufficiently to permit the end of the same, including the projections 11, to pass through the window, and then to lower the bolster, bringing said projections into the openings 10 provided therefor. 55

It will be apparent that I have provided a construction which is not only simple and inexpensive to manufacture, but also readily assembled. Moreover, it is capable of being incorporated in trucks of known construction without any com- 75

plicated or even substantial changes in the structure of these trucks. In this way all the advantages of the construction shown in my co-pending application referred to are retained 5 while at the same time there is secured the additional effect of damping out undesirable oscillations, and reducing the recoil.

While this invention has been described in connection with the construction shown in my 10 aforesaid co-pending application, it will be understood that the novel features disclosed are susceptible of embodiment in other types of car trucks, as will be apparent to one skilled in the art. Moreover, the terms and expressions which 15 I have employed are used as terms of description and not of limitation, and I have no intention, in the use of such terms and expressions, of excluding any equivalents of the features shown and described or portions thereof, but recognize 20 that various modifications are possible within the scope of the invention claimed.

I claim:

1. In a car truck including a bolster and side frame, a shelf formed on the side frame, a spring 25 on the shelf supporting the bolster, a spring supported on the side frame below the shelf and means between said shelf and said second named spring for spacing the latter from the under side of said shelf, whereby said second named spring 30 is adapted to engage the bolster only after predetermined compression of the first named spring.

2. In a car truck including a bolster and side frame, columns on said side frame, a shelf formed 35 on the side frame extending between said columns, a spring on the shelf supporting the bolster, a spring supported on the side frame below the shelf and means comprising a portion of said shelf adapted to maintain said second named 40 spring under initial compression for engagement with the bolster only after predetermined compression of the first-named spring.

3. In a car truck including a bolster and side frame, a spring supported on the side frame and 45 engaging the bolster, a window formed in the side frame for receiving the end of the bolster, a spring substantially entirely below the window supported on the side frame and adapted to be engaged by the bolster only after predetermined compression 50 of the first-named spring, and means comprising a portion of said side frame above said second named spring for placing the latter under initial compression.

4. In a car truck including a bolster and side frame, a spring supported on the side frame and 55 engaging the bolster, a window formed in the side frame for receiving the end of the bolster, a spring substantially entirely below the window supported on the side frame and adapted to be engaged by the bolster only after predetermined compression 60 of the first-named spring, and means comprising a portion of said side frame above said second named spring for placing the latter under initial compression.

5. In a car truck including a bolster and side frame, a shelf formed on the side frame, a spring 65 on the shelf supporting the bolster, a spring supported on the side frame below the shelf and adapted to engage the bolster after predetermined compression 70 of the first-named spring, and means interposed between said shelf and last-named spring for placing the latter under initial compression.

6. In a car truck including a bolster and side frame, a shelf formed on the side frame, a spring 75

on the shelf supporting the bolster, said shelf having an opening formed therein and said bolster having a projection extending through said opening, a spring supported on the side frame below the shelf and adapted to engage the bolster after predetermined compression of the first-named spring, and a collar operatively interposed between the shelf and the last-named spring for placing the latter under initial compression, said collar substantially surrounding 10 the lower end of the bolster projection.

7. In a car truck including a bolster and side frame, a shelf formed on the side frame, a spring on the shelf supporting the bolster, a plurality of springs supported on the side frame below the shelf and means between said shelf and the second named springs providing for the successive engagement of the latter with the bolster after predetermined compression of the first-named spring. 15

8. In a car truck including a bolster and side frame, a shelf formed on the side frame, a spring on the shelf supporting the bolster, and a plurality of springs under different amounts of initial compression supported on the side frame 20 below the shelf and adapted successively to engage the bolster only after predetermined compression of the first-named spring. 25

9. In a car truck including a bolster and side frame, a shelf formed on the side frame, a spring 30 on the shelf supporting the bolster, a spring supported on the side frame below the shelf, a spring seat on the top of the second-named spring adapted to be engaged by the bolster, and means carried with the spring seat and adapted to engage the 35 shelf for spacing the spring seat from the bolster prior to movement of the latter to compress the first-named spring.

10. In a car truck including a bolster and side frame, a shelf formed on the side frame, a spring 40 on the shelf supporting the bolster, a spring supported on the side frame below the shelf, a spring seat on the top of the second-named spring adapted to be engaged by the bolster, and means carried with the spring seat and adapted to engage 45 the shelf for spacing the spring seat from the bolster prior to movement of the latter to compress the first-named spring, and for maintaining the second-named spring under initial compression. 50

11. In a car truck including a bolster and side frame, a shelf formed on the side frame, a spring on the shelf supporting the bolster, a spring supported on the side frame below the shelf, and means operatively interposed between the second-named spring and said shelf for spacing said second named spring from the under side of the shelf to thereby provide for compression of the second-named spring by the bolster only after predetermined compression of the first-named spring. 55

12. In a car truck including a bolster having a projection, and a side frame, columns on said side frame, a shelf formed on the side frame and extending between said columns, a spring on the shelf supporting the bolster, a projection on the bolster extending into an opening in said shelf and a spring under initial compression supported on the side frame below the shelf and adapted to engage said bolster projection only after predetermined compression of the first-named spring. 60

13. In a car truck including a bolster and side frame, a shelf formed on the side frame, a spring on the shelf supporting the bolster, a spring supported on the side frame below the shelf, a spring seat on the top of the second-named spring, and 70

means operatively interposed between said second-named spring and said shelf, and constructed and arranged to position the second-named spring with respect to the bolster, said second-named spring being adapted for engagement by the bolster only after predetermined compression of the first-named spring, and said means being separable from said spring seat.

14. In a car truck, a bolster, a side frame having 10 columns and a shelf extending between said columns, said bolster extending into the space between said columns and having a lug extending into an opening in said shelf, spring means above said shelf for supporting said bolster, spring 15 means mounted on said side frame entirely below said shelf, and means comprising a portion of said shelf for maintaining the second mentioned

spring means in position for engagement with said bolster lug only upon a predetermined compression of the first-named spring means.

15. In a car truck including a bolster and side frame, a shelf formed on the side frame, a spring on the shelf supporting the bolster, a spring supported on the side frame below the shelf, and means operatively interposed between the second named spring and said shelf and constructed and arranged to provide for compression of the second named spring by the bolster only after predetermined compression of the first named spring, said second named spring being arranged to be compressed vertically by said bolster during the downward movement of the latter. 10 15

JAMES A. SHAFFER.
